UNITED STATES PATENT OFFICE.

JOHN E. BELL, OF NEW YORK, N. Y., ASSIGNOR TO THE BABCOCK & WILCOX COMPANY, OF NEW YORK, N. Y., A CORPORATION OF NEW JERSEY.

WATER-TUBE BOILER.

No. 857,016.

Specification of Letters Patent.

Patented June 18, 1907.

Application filed May 21, 1906. Serial No. 317,854.

To all whom it may concern:

Be it known that I, JOHN E. BELL, of New York, county and State of New York, have invented a new and useful Water-Tube Boiler, of which the following is a full, clear, and exact description, reference being had to the accompanying drawings, forming a part of this specification, in which—

The figure is a sectional side elevation of a boiler constructed in accordance with my invention.

My invention relates to that class of water tube boilers, wherein transverse upper steam and water drums are connected by banks of tubes to a lower transverse mud drum or drums, the source of heat being in front of the front bank, and the gases flowing in successive up and down passes across successive banks.

The object of the invention is to provide a simple and efficient system for adding heating surface between the banks of tubes, especially where two banks are employed.

In the drawings, 2 and 3 represent two upper steam and water drums, and 4 and 5 represent corresponding mud drums. These drums are connected by the banks of tubes 6 and 7 and also by the two rows of baffle tubes 8 and 9 which extend upwardly on either side of the baffle wall 10. The tubes 8

and 9 are preferably curved at their lower ends to enter the mud drum on each side of the pier or wall 11 supporting the baffle. The upper ends of tubes 8 and 9 enter a water chamber or chambers 12 which extends transversely between the banks of water tubes, and is in the upper part of the boiler and above the top of the baffle 10. The water chamber 12 is preferably connected with both steam and water drums by tubes or nipples 13 and 14.

15 represents the furnace from which the gases rise among the first bank and pass over the top of baffle 10 and descend among the tubes of the rear bank. The baffle is preferably provided with shelves 16 which tend to hold the gases in the main banks and shield the baffle tubes 8 and 9 so as to make them relatively cooler than the tubes of the adjacent main banks.

In the operation of the boiler the gases rise among the tubes of the front bank and heat the tubes 8 to some extent, and then descend among the tubes of the rear bank to the out-

let flue 17 while heating the tubes 9 to some extent. The circulations are probably as follows: Up through the front bank 6 and down through the nipples 13 into chamber 12; also up through the rear bank 7 and down through nipples 14 into chamber 12. The water of chamber 12 will pass down through the two rows of tubes and be directed into both mud drums. The circulations therefore are probably in the nature of two cycles which commingle in the drum or chamber 12 above the top of the baffle.

The advantages of my invention result from the simple, cheap and efficient manner of adding heating surface between the banks and from the peculiar connections and circulations for such added surface.

The water spaces of the steam and water drums may be provided with direct connecting or circulating tubes, nipples or pipes may be used to directly connect the mud drums, the pipes 14 may be omitted, straight or curved tubes may be used in the main banks, the chamber 12 may be in the form of a drum, a long header or a series of short headers, a single mud drum may be used with either one or two compartments, and many other changes may be made without departing from my invention.

I claim:

1. A water tube boiler having upper transverse steam and water drums, each connected by a bank of tubes to a lower transverse mud drum, a water chamber in the upper part of the boiler between the main banks of tubes and connected to the water space of at least one of the steam and water drums, rows of tubes leading downwardly from the water chamber and connecting it directly to the mud drums, and a baffle extending between the latter tubes and terminating below the water chamber; substantially as described.

2. A water tube boiler having two transverse steam and water drums each connected by a bank of tubes to a transverse mud drum, a transverse water chamber extending between the banks of tubes in the upper part of the boiler and connected to the water spaces of both steam and water drums, and tubes leading downwardly from said water chamber and connecting directly into both mud drums; substantially as described.

3. A water tube boiler having two transverse steam and water drums each connected

by a bank of tubes to a transverse mud drum, a transverse water chamber extending between the banks of tubes in the upper part of the boiler and connected to the water spaces of both steam and water drums, and tubes leading downwardly from said water chamber and connecting directly into both mud drums, and a baffle extending upwardly between the latter tubes and terminating below the water chamber; substantially as described.

4. A water tube boiler having upper transverse steam and water drums, each connected by a bank of tubes to a transverse mud

drum, a transverse water chamber extending 15 between the banks of tubes in the upper part of the boiler, and connected to the water space of one of the steam and water drums, and tubes leading downwardly from said water chamber, and connecting directly into 20 both mud drums; substantially as described.

In testimony whereof, I have hereunto set my hand.

JOHN E. BELL.
